CASTER

Filed May 9, 1923

Inventor
Byrnett Mcintosh,
By his Attorney
Frank J. Kent

UNITED STATES PATENT OFFICE.

BURTNETT MCINTOSH, OF NEW YORK, N. Y.

CASTER.

Application filed May 9, 1923. Serial No. 637,689.

This invention relates to casters, and more particularly aims to provide new and valuable improvements in furniture casters, especially for hospital furniture, such as beds.

It is a fact that caster structures for hospital beds have long been sought which shall at once include caster wheels quickly and freely rotatable about their horizontal axes, and journalling structures quickly and freely rotatable about vertical axes, and yet which shall also be instantaneously, conveniently and securely lockable as to both such axes at will; which shall be attachable to and replaceable on the lower leg portions of the beds, yet provided with anti-friction revoluble members as well for the vertical axes as for the horizontal ones; which shall be provided with means for locking each wheel in one of a multiplicity of angular adjustments relative to its journalling support, and also for locking the plane of rotation of the wheel in any one of a multiplicity of angular adjustments relative to the length of the bed; and which shall be generally of compact, attractive, rugged and durable yet inexpensive construction.

The prime object of the invention is to provide a caster, a practical embodiment of which will attain all the ends just set forth.

The invention will be best understood from a consideration of the following detailed description when taken in connection with the accompanying drawing forming part of this specification; with the understanding, however, that such drawing illustrates, merely by way of example, one possible embodiment of the invention, and that the invention is not confined to any strict conformity with the showing in the drawing, but may be changed and modified so long as such changes and modifications mark no material departure from the salient features of the invention as expressed in the appended claims.

In said drawing, Figure 1 shows the new caster with the wheel in edge elevation, fitted to a lower hollow leg portion of an article of furniture, such portion being shown in section;

Figure 2 is a view similar to Figure 1, but a view showing the wheel in side elevation;

Figure 3 is a view similar to Figures 1 and 2, in that the journalling axis of the wheel and the vertical axis of the journalling structure are normally unlocked, but being, however, a vertical sectional view taken sub-

stantially on the line 3—3—3 of Figure 1; and

Figure 4 is a view also on the section line 3—3—3 of Figure 1, but showing the wheel locked against rotation and against changing its plane of rotation relative to the length of the bed.

The furniture leg 5 is tubular at its lower end, as is usual, to provide the familiar vertical bore 6.

Fitted into the hollow of the leg 5 is a vertical stud 7 of common design, and this stud is preferably provided with vertical flutings 8 heretofore often adopted in the caster art, but in the present case to serve a useful purpose in permitting the employment of a very simple means for limiting predetermined telescopic adjustments between stud 7 and a secondary stud 9 slidably and rotatably accommodated with in a hollow portion 10 of stud 7.

The simple stop means just referred to includes a unitary resilient instrumentality 11 comprising a single length of spring wire 80 bent at its middle portion into a spring-eye 12, beyond which the wire is prolonged as a pair of downwardly extending arms accommodated in two diametrically opposite flutings or grooves 8, except for the free end portions of arms 11, which portions, marked 13 in Figure 4, are inturned toward each other and passed through suitable slots or openings in secondary stud 9. These openings are marked 14 in Figure 4; and beyond them the tops of portions 13 protrude into the peripheral groove of secondary stud 9 between shouldered portions 15 thereof.

The construction just described provides not only the limiting means aforesaid, but, it will be seen, affords an anti-friction journalling mounting for secondary stud 9 relative to stud 7, by virtue of the reduced peripheral surfaces of the secondary stud 100 movable relative to the socket mounting provided at the lower end of the furniture leg.

Below secondary stud 9 is carried a stud-enlargement 9' slidable vertically through a lower-cap structure 7' formed integral with main stud 7.

Secondary stud enlargement 9' is secured at its bottom to the upper portion of a yoke 16 the forked lower ends of which carry a journalling stud 17 for wheel 18.

Fixed to one side of the wheel is a circumferentially toothed member 18' of spur

gear form, presenting a multiplicity of radially extending recesses or keepers, each located between a pair of gear-toothed projections 19. A link 20 carrying a bolt or

5 dog 20' to co-act with any one of the keepers of member 18 is given a pin and slot mounting on journalling stud 17, by means of such stud and a slot 21 in the lower end of the link. The upper end of this link

10 is pivoted to yoke 16 at 22, as is also a treadle-lever 23 presenting a pedal arm 24.

This treadle-lever 23 also has an arm 25 to which is pivoted, at 26, the lower end of an upwardly extending bar 27 shaped at its

15 top to present a dog 28 relative to another circumferentially arranged multiplicity of recesses or keepers, but in a horizontal plane. These recesses or keepers are presented be-

20 tween depending teeth formed on the under-side of a spur-gear type member 29 carried integrally by lower cap-structure 7' and hence by main stud 7. Intermediate its ends, arm 27 passes loosely through a slot 30 in the upper end of yoke 16.

25 Treadle-lever 23 also carries a horizontally offset rounded portion 31 adapted to constitute, with the multi-wave shaped upper edge portion of link 20 indicated at 32 in broken lines in Figures 3 and 4, an impositive latching means for helping to hold the parts set when adjusted either as shown in Figure 3 or Figure 4.

Operation.

35 With the parts arranged as shown in Figures 1; 2 and 3, it is obvious that a hospital bed, the lower portions of all four legs of which are equipped with the construction shown and described, may be quickly and 40 freely rolled about the floor of a hospital room in any direction or directions; until the bed is positioned exactly as required for the purpose then in mind. Thereupon the attendant applies his foot to pedal arm 24,

45 and depresses the same to the position shown in Figure 4. Simultaneously therewith, the link 20 moves downward to the right of Figure 3, and the dog 20' engages member 18 as shown in Figure 4 and locks the wheel 50 against rotation on its journalling stud 17.

Also, the dog 28 is moved up and engages member 29 as shown in Figure 4. Further, to permit the pedal arm 24 to be lowered fully to the position of Figure 4, to throw 55 the pivot-studs 26 and 22 into vertical alignment and hence to arrange the parts at dead center, and to cause projection 30 to enter into impositive latching engagement with the upper wave depression of the shaped edge 60 32 of link 20, the link raises main stud 7, leg 5, and the wire spring stop device 11, relative to secondary stud 9 and all the parts therebelow.

65 It will be understood of course that each of the four legs of the bed is preferably

equipped with a caster like the one illustrated, so that these casters, one after another, will be thrown by the attendant from the adjustment of Figure 3 to that of Figure 4.

Variations may, of course, as hereinabove indicated, be resorted to within the scope of the following claims.

I claim:

1. In a caster, in combination, a caster wheel, a vertical stud for upward insertion into the hollow lower leg portion of an article of furniture, said stud being hollow, a supporting structure for the wheel caster including a secondary upstanding stud adapted to be rotatably seated in the hollow stud, and means for simultaneously causing relative movement of the wheel and one of the studs relative to the other stud, and means thereupon automatically brought into play for locking the wheel against rotation relative to the supporting structure and against changing its plane of rotation relative to both studs.

2. In a caster, in combination, a caster wheel, a supporting structure for the wheel axis adapted to be rotatably mounted on the lower leg portion of an article of furniture, and pedal actuated means for simultaneously locking the supporting structure against rotation relative to said leg portion and for locking the wheel against rotation relative to the supporting structure.

3. In a caster, in combination, a caster wheel, a supporting structure for the wheel axis adapted to be mounted on the lower leg portion of an article of furniture, means for locking the wheel against rotation relative to the supporting structure, and means for thereupon automatically locking the wheel against changing its plane of rotation relative to the article of furniture, there being an actuating pedal common to both said means movably mounted on the supporting structure.

4. In a caster, in combination, a caster wheel, a supporting structure for the wheel axis adapted to be mounted on the lower leg portion of an article of furniture, means for moving such furniture leg upwardly relative to the journalling axis of the wheel, and means for thereupon locking the wheel against changing its plane of rotation on said axis.

5. The caster defined in claim 4, wherein means are further provided for limiting said movement of said leg.

6. The caster defined in claim 4, wherein means are further provided for positively limiting said movement of said leg, said means including a resilient instrumentality.

7. In a caster, in combination, a caster wheel, a supporting structure for the wheel axis adapted to be mounted on the lower leg portion of an article of furniture, means for locking the wheel abnormally relative to the

bed, and means for thereupon raising the bed relative to the wheel thereby to lock said locking means against accidental release.

8. The caster defined in claim 7, wherein a pedal actuator is provided and said locking means is operatively connected thereto, such operative connection including a plurality of members pivotally attached at a plurality of points, one of such pivots being movable with a member and the latter pivot becoming vertically aligned with another pivot when the bed raising means raises the bed.

9. A caster comprising a socket member

for upward insertion into the hollow lower leg portion of an article of furniture, a stud 15 rotatably fitting within the socket, a yoke secured to the stud, a wheel rotatably mounted in the yoke, stop members formed on the wheel, a foot lever pivoted to the yoke, an arm pivoted to the foot lever and adapted 20 to engage the socket, and a second arm pivoted to the foot lever and adapted to engage the stop members formed on the wheel.

In testimony whereof I affix my signature.

BURTNETT McINTOSH.
